GOLF SWING CO-ORDINATOR GAUGE

Francis M. Olson, Los Angeles, Calif.

Application October 31, 1958, Serial No. 53,230

Term of patent 14 years

(Cl. D34—5)

Figure 1 is a plan view of a golf swing co-ordinator gauge showing my new design; the opposite side having the same appearance;

Figure 2 is an edge view looking to the right of Figure 1;

Figure 3 is an edge view looking to the left of Figure 1;

Figure 4 is an edge view looking in the direction of the bottom of Figure 1; and

Figure 5 is an edge view looking toward the top of Figure 1.

I claim:

The ornamental design for a golf swing co-ordinator gauge, substantially as shown and described.
